(57) **CLAIM**

The ornamental design for scissors for cutting hair, as shown and described.

DESCRIPTION

FIG. 1 is a front elevational view of scissors for cutting hair showing my new design;

FIG. 2 is a top plan view thereof;

FIG. 3 is a right side elevational view thereof;

FIG. 4 is a left side elevational view thereof;

FIG. 5 is a rear elevational view thereof; and

FIG. 6 is a bottom plan view thereof.

FIG. 7 is an enlarged top plan view of FIG. 2, wherein a ring is in a rotated position;

FIG. 8 is an enlarged is a top plan view of FIG. 2, wherein the ring and a holding part are in a rotated position;

FIG. 9 is a left side elevational view of FIG. 3, wherein the ring and the holding part are in a rotated position; and,

FIG. 10 is a left side elevational view of FIG. 3, wherein the holding part are in a rotated position.

The broken lines illustrate unclaimed portions of the scissors for cutting hair and form no part of the claimed design. The knob illustrated with broken lines located on the handle portion of the scissors forms no part of the claimed design. The dot-dash broken lines which define the bounds of the claimed design form no part thereof.
